UNITED STATES PATENT OFFICE.

CHARLES BART, OF KEW GARDENS, NEW YORK.

COAT HANGER.

Application filed February 24, 1925. Serial No. 11,057

To all whom it may concern:

Be it known that I, CHARLES BART, a citizen of the United States, and residing at Kew Gardens, L. I., in the county of Queens and State of New York, have invented certain new and useful Improvements in Coat Hangers, of which the following is a specification, such as will enable those skilled in the art to which it appertains to make and use the same.

This invention relates to coat hangers and particularly to devices of this class provided with means for gripping and retaining a garment in connection therewith to prevent the accidental displacement thereof; and the object of the invention consists in providing a garment hanger of general form and providing the side portions thereof with movably disposed gripping jaws normally retained in operative position under tension and adapted to be moved into inoperative position by hand; a further object being to provide the gripping jaws of devices of the class specified composed of a single strand of wire fashioned to form the jaw member proper, and the pivoted end portion thereof as well as the means for applying tension to the jaw member; and with these and other objects in view, the invention consists in a device of the class and for the purpose specified which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a side view of a hanger made according to my invention and showing one of the jaw members in a raised position.

Fig. 2 is a plan view of the construction shown in Fig. 1, with part of the construction broken away.

Fig. 3 is a section on the line 3—3 of Fig. 1 on an enlarged scale; and,

Fig. 4 is a plan view of a detail of the construction as shown in Fig. 2 and on an enlarged scale.

In practice, I provide a garment hanger comprising the usual arcuate garment receiving portion 5, centrally of which is the upstanding hook member 6 or other device for supporting the part 5 in connection with a suitable support, and at 7 I have shown

two of my improved jaw members or clamp devices for retaining a garment against displacement from the part 5.

The invention is adapted primarily for use in connection with dresses, shirt waists and like garments, and principally garments of this class which are apt to become displaced from the hanger when in use, and the jaw members or devices 7 are adapted to cooperate with such garments when mounted on the part 5 to frictionally retain them against accidental displacement and said jaw members or devices are so constructed as to facilitate the detachment of the hanger from the garment, whenever desired, in a simple and effective manner.

In the construction shown, each of the jaw members or devices 7 is composed of a single strand of wire bent centrally to form an elongated loop 8, the end of which flares upwardly as seen at 9 in Fig. 1 of the drawing and connected with the side members of the loop 8 is a transverse felt strip 10 adapted to bear upon the top part 5 of the hanger or the garment thereof as will be apparent. It will also be noted that the side members of the loop 8 are adapted to overlap the part 5 to form a gripping jaw or member, while the felt or other fabric strip 10 serves as means for protecting the garment and will prevent the same from becoming torn or defaced in any way. The side members of the loop 8 are brought together into parallel relation as seen at 11 in Fig. 2 of the drawing, and adjacent the other end portion of the device 7, the wire is fashioned to form oppositely disposed offset portions 12, and the ends of the wire continue backwardly and are curved downwardly as shown at 13 and upwardly as shown at 14, and are also flared laterally as indicated at 15 in Fig. 4 of the drawing to form finger pieces by means of which the device is operated, and the ends of the wire after being flared laterally and bent upwardly are bent downwardly and forwardly to form open loops 16 and are then bent to form eyes 17 through which a pivot pin or eyelet 18 passes, and the free end portions of said wire after passing around the pivots 18 extend upwardly as shown at 19, and the end portions are bent inwardly and downwardly into the offset portions 12 as seen at 20, and said end portions may be soldered in position and to the offset portions 12 of the wire to form a unitary construction. It

100

105

110

will be apparent that the end portions 19 of the wire are secured in position to give tension to the loop end 8 of the device 7, and said end portions also serve, when secured in position, to prevent the separation of the rod where brought together or in parallel relation as seen at 11.

The pivot pins or eyelets 18 are mounted in the part 5 of the hanger as clearly seen in the drawing and preferably so arranged as to give the proper or desired tension to the jaw members or devices 7. It will be apparent that the upstanding end portions 19 are directed forwardly or in off-centered position when the jaw members or devices 7 are in operative position, and by applying the fingers of a hand in the depressions 13 and forcing said end portions of the devices downwardly as seen in dot and dash lines at the right of Fig. 1 of the drawing, the loop end portions 8 may be raised out of engagement with the part 5, and if the depression of the devices 7 is sufficient, the same will assume a position substantially similar to that illustrated in dot and dash lines in said figure. The movement of the devices 7 to release a garment from the part 5 need only be very slight and the entire operation may be accomplished by one hand of an operator, two fingers of the hand being placed in the grooves 13 of the separate devices with the thumb of the hand beneath the central portion of the part 5.

I am well aware of the fact that there are other devices in use which operate to accomplish the result accomplished by my improved device, but in most cases, the devices now in use require the use of the two hands in their manipulation or are of such complicated construction that the costs thereof are prohibitive to render the same commercially valuable. The distinctive feature of my invention resides in the provision of a simple, practical and efficient jaw member or clamp device for garment hangers of the class under consideration, and particularly to the construction of a device of this class of a single piece of material. While I have shown certain details of construction for carrying my invention into effect, it will be understood that I am not necessarily limited to the construction herein shown and described, and various changes therein and modifications thereof may be made within the scope of the appended claims without departing from the spirit of my invention or sacrificing its advantages.

Having fully described my invention, what I claim as new and desire to secure by Letters Patent, is:—

1. A garment hanger, the side portions of which are provided with clamp devices for frictionally retaining a garment against dis-

placement on said hanger, said devices comprising an outer or jaw portion, an inner portion pivotally mounted in connection with the hanger and provided with a finger piece for moving the jaw portion into inoperative position, and means on the pivot of said device and cooperating with the pivot end portion thereof for normally holding the jaw member of the device in operative position under tension. 79

2. A garment hanger, the side portions of which are provided with clamp devices for frictionally retaining a garment against displacement on said hanger, said devices comprising an outer or jaw portion, an inner portion pivotally mounted in connection with the hanger and provided with a finger piece for moving the jaw portion into inoperative position, means on the pivot of said device and cooperating with the pivot end portion thereof for normally holding the jaw member of the device in operative position under tension, and the several parts of the device being of unitary construction. 75

3. A clamp device for use in connection with garment hangers, said device being fashioned from a strip of wire to form an elongated loop at one end, said wire being brought together into substantially parallel relation throughout the shank of the device and the end portions of said wire being fashioned to form finger pieces, eyes through which a pivot pin is adapted to pass, and end portions engaging the shank adjacent the finger pieces thereon. 93

4. A clamp device for use in connection with garment hangers, said device being fashioned from a strip of wire to form an elongated loop at one end, said wire being brought together into substantially parallel relation through the shank of the device and the end portions of said wire being fashioned to form finger pieces, eyes through which a pivot pin is adapted to pass, and portions engaging the shank adjacent the finger pieces thereon, and said end portions, when the device is in use, serving to hold the loop-shaped end portion in operative position under tension. 105

5. In a garment hanger, a device for frictionally retaining a garment against displacement from the hanger comprising a body of unitary construction provided at one end with an elongated loop and at the other end with flared open loops fashioned to form finger pieces, the ends of said loops terminating in angularly disposed members engaging the shank of the body to form a yoke, and said ends having eyes through which a pivot pin is adapted to pass. 110

In testimony that I claim the foregoing as my invention I have signed my name this 21st day of February 1925.

CHARLES BART.
